UNITED STATES PATENT OFFICE.

MAURICE J. SCHLESS, OF NEW YORK, N. Y., ASSIGNOR TO SCHLESS, BROD & CO., OF NEWARK, NEW JERSEY, A FIRM COMPOSED OF MAURICE J. SCHLESS, ALBERT BROD, AND OSCAR J. BROD.

KNIFE.

1,182,043.

Specification of Letters Patent.

Patented May 9, 1916.

Application filed September 25, 1915. Serial No. 52,556.

To all whom it may concern:

Be it known that I, MAURICE J. SCHLESS, a citizen of the United States of America, residing at New York city, in the county 5 and State of New York, have invented certain new and useful Improvements in Knives, of which the following is a specification.

My invention relates to improvements in 10 cutlery, and as it is especially applicable to ornamental pocket knives, it will be described in that connection. It will be understood that the invention may be applied to other articles than knives, such as forks, 15 combination sets, and the like.

Pocket knives are now on the market in 20 which the side plates of the handle are covered with gold or other precious metal. In the manufacture of such knives, the present practice is to first cover the side plates of 25 the handle with the desired ornamental metal, then assemble the blades in the handle, and finally drive the rivets through the handle and blades to complete the article. This practice has several serious disadvantages. In driving the rivets through the 30 usually thin covering of gold, the latter is apt to be injured, often spoiling the appearance of the knife, and at times rendering the gold covering useless. Again, in a knife 35 constructed as above described, if a blade is broken or injured, and requires to be replaced or repaired, it is necessary to force out the rivets (which serve largely to hold the gold in place) remove the gold from 40 the side plates, disassemble the structure, replace the broken blade, then put the gold back in position, and finally drive the rivets back into the ends of the knife. Repair work of this kind is almost as expensive as 45 the initial cost of the knife, and consequently the owners of broken or injured knives hesitate to have the same repaired.

With the foregoing in view, the principal 50 object of my invention is to provide a knife structure, capable of being provided with a precious metal covering for the handle plates, which is so devised that the knife may be quickly assembled and disassembled with the aid of simple tools, and in which all injury to the gold or other precious metal covering is obviated.

A further object is to provide means, other than the usual rivets, for retaining the

gold covering firmly in position on the handle plates, and dispensing with the need for its removal in case the knife is repaired, or disassembled for any other purpose.

A still further object is to provide a novel arrangement of spring, conducing to simplicity of construction and handling the parts of the knife in assembling and disassembling the same.

Other objects of my invention, and its detail structure and operation, will be fully 65 set forth in the following specification, reference being had to the accompanying drawing, in which—

Figure 1 is a side elevational view of a pocket knife embodying my invention, the 70 gold covering on one side of the handle being indicated as broken away; Fig. 2 is a vertical sectional view, on the line 2—2 of Fig. 1, looking in the direction of the arrows; Fig. 3 is a side elevational view of a 75 fragment of a handle plate, showing on a somewhat enlarged scale the slot near the end of the plate; Fig. 4 is a similar view of a knife with one of the handle plates and one of the blades omitted; Fig. 5 is an elevational view of a spring bail which I may employ at either end of the knife; Fig. 6 is a similar view of the parts of a hollow rivet which I preferably use to hold the 80 blades and handle plates assembled; Fig. 7 85 is a vertical sectional view of the assembled hollow rivet; and Fig. 8 is a fragmentary sectional view illustrative of an angular undercut groove in the handle plates for anchoring the edge of the gold covering of 90 the handle.

Referring to the drawing by reference characters, 10 denotes the side plates of the handle. Each side plate has formed on its inner face an undercut, angular, groove 11 95 which extends entirely around the plate a short distance in from its edge. This groove has the function of receiving and anchoring the marginal edges of the gold covering 12 for the handle. This covering 100 is in the form of a relatively thin sheet of gold, which is drawn smoothly over the outer face of the handle plate 10, and its marginal edges are then turned over or upset and stamped or otherwise forced into 105 the grooves 11 so as to be firmly anchored therein.

Each plate 10 is provided near each of its

ends with an elongated, preferably two-branch slot, designated generally as 13, which may be of substantially angular or arcuate form. Each slot 13 is of such construction and form that when a blade pivot is at one end of the slot the blade carried thereby may be opened and closed but not removed from the handle, while if the pivot is at the other end of the slot, the blade and pivot may be bodily removed from the handle, and the knife disassembled.

At the end nearest the center of the knife, the slot portion 13^a is of a greater diameter than at any other point, and when the pivot, shown in Figs. 6 and 7 and hereinafter fully described is in the portion 13^a this pivot may be withdrawn from engagement with the handle plate. The walls of the balance of the slot are undercut as at 13^b, and thus not only form a guide and support for the pivot during its movement in the slot, but also act to prevent withdrawal of the pivot from the handle when the pivot is in the slot portion 13^c, or at any other part than 13^a.

I have found it most convenient, in practice, to employ a pivot for the knife blades such as shown in Figs. 6 and 7. This pivot embodies a hollow hub number 14, having an integral annular flange 15 at one end and an integral reduced neck portion 16 at its opposite end. Below the neck is a shoulder 17 designed to support a second flange 18 which is clamped to the pivot by upsetting the neck 16 over the upper face of the flange 18, as shown in 7. It will of course be understood that each blade has an orifice in its shaft through which the hub 14 passes and which serves as a pivot about which the blade may revolve. The blades are of any approved construction.

Ornamental knives of the character contemplated by this invention are frequently attached to watch chains, and to facilitate attachment of the knife I may provide the latter with a bail 20 (Fig. 5), made of suitable spring metal, gold plated or otherwise, and having the inturned ends 20^a designed to be sprung into and removed from the opposite open ends of the pivot.

The spring which I preferably employ is denoted 21 (Fig. 4), and is of sufficient length to have its opposite ends press against the shafts of the knife blades 19. The spring has a central enlargement 21^a in which is rigidly secured a stud 22 projecting beyond both lateral faces of the spring 21. The opposite ends of this stud enter suitable orifices formed near the center of the lower edge in each handle plate 10. The spring 21 is preferably slightly shorter than the plates 10 and stops short of each end of the latter.

A knife embodying the features of my invention is assembled as follows:—It is as-

sumed that the handle plates 10 are covered with the gold sheet 12 and the edges of the latter anchored in the groove 11, and also that the pivots have been passed through the holes in the blades and the flanges 18 secured to the hub 14. One plate 10 is laid flat on a support and the spring 21 placed in position by passing the stud 22 through the orifice in that plate. Then either the flanges 15 or 18, it is immaterial which, are passed through the portions 13^a of the slots 13, the blades being in the opened out position. Thereafter the other handle plate 10 is superimposed on the blades so that its slot portions 13^a exactly coincide with the flange 15 or 18, as the case may be. The blades 19 are then drawn toward the ends 13^c of the slots 13 and during this operation the flanges 15 and 18 will ride on the undercut walls 13^b and be prevented from lateral movement. When the pivots reach the slot portions 13^c the knife is completely assembled, the blades being capable of free opening or closing movement, as desired. If it be desired to provide the knife with the bail shown in Fig. 5, the gold cover 12 on opposite handle plates at one end of the knife, in portions aligned with the openings in one of the hubs 14 is pierced with a clean cut hole, and the ends 20^a of the bail spring into the hub. It will be noted that the entire structure is held in assembled position by coaction of the flanges 15 and 18 with the undercut walls 13^b of the slot 13.

To disassemble the knife, for the removal of an old blade and the insertion of a new, or for any other purpose, the procedure is as follows:—First, remove the bail 20 by spreading its arms apart, and then, by means of any suitable tool, draw or force the blades inwardly toward each other, until the pivots of the blades coincide with the slot portions 13^a. In this position of the parts it is simply necessary to lift one or the other handle plate 10 and all the parts may be separated. In thus disassembling the knife the gold sheathing 12 is neither disturbed nor injured, and all the rivets and pivots come out with the parts to which they are operatively related. As a result of my invention the knife may be originally produced at a lower cost than heretofore; the article is usually of better and more finished appearance; and the cost of repairs is greatly reduced.

What I claim as new and desire to secure by Letters Patent is:—

1. As an article of manufacture, a knife comprising independent handle plates each having an angular slot adjacent an end thereof, a pivot passing through and movable along said slots, means carried by said pivot and engageable with and disengageable from the walls of said slots whereby said handle plates may be connected to

gether or freed from each other, a blade carried by said pivot, and means connecting the other ends of said plates together.

2. As an article of manufacture, a knife comprising independent handle plates each having angular slots at its opposite ends, pivots passing through and movable along said slots, heads carried by said pivots and engageable with and disengageable from the walls of said slots whereby said handle plates may be connected together or freed from each other, and blades carried by said pivots.

3. As an article of manufacture, a knife comprising independent handle plates each having elongated angular slots at its opposite ends, pivots passing through and movable along said slots, means carried by said pivots and engageable with and disengageable from the walls of said slots whereby said handle plates may be connected together or freed from each other, and blades carried by said pivots.

4. As an article of manufacture a knife comprising independent handle plates each having angular slots with undercut walls at opposite ends thereof, pivots passing through and movable along said slots, heads carried by said pivots and engageable with and disengageable from the undercut walls of said slots, and blades carried by said pivots.

5. As an article of manufacture, a knife comprising independent handle plates each having adjacent each of its ends a slot

widened at one end thereof, pivots passing through and movable along said slots, heads carried by said pivots and removable through the widened ends of said slots, and blades carried by said pivots.

6. As an article of manufacture, a knife comprising a handle having near one end thereof an angular slot with undercut walls, said slot being wider at one end than at any other portion thereof, a pivot having an enlarged head, said head being removable through the enlarged end of said slot and capable of riding on the undercut walls thereof, a blade carried by said pivot, and a spring in said handle adapted to bear against said blade.

7. As an article of manufacture, a knife comprising oppositely disposed independent handle plates, each of said plates having elongated slots at its opposite ends and an undercut groove in one face near the edge of the plate, pivots movable along and engageable with and disengageable from said slots to connect the plates together or to free the same from each other, a sheathing for each plate covering the outer face thereof and having its marginal edges anchored in the undercut groove in such plate, and blades carried by the pivots.

In the testimony whereof I have affixed my signature in presence of two witnesses.

MAURICE J. SCHLESS.
